United States Patent

Des. 234,931
Patented Apr. 22, 1975

234,931

DISPLAY STAND

Harry Rogove and Roslyn Rogove, Bayside, N.Y., as signors to Remember When Sweet Shoppe, Inc., Valley Stream, N.Y.

Filed June 22, 1973, Ser. No. 372,596

Term of patent 14 years

Int. Cl. D20—02

U.S. Cl. D6—25

FIG. 1

FIG. 2

FIG. 3

FIG. 4

FIG. 1 is a top plan view of the design for a display stand, showing particularly the roof portion thereof;

FIG. 2 is a front elevational view thereof;

FIG. 3 is a bottom plan view thereof; and

FIG. 4 is a bottom sectional view thereof taken along the line 4—4 of FIG. 2.

We claim:

The ornamental design for a display stand, as shown and described.
